(57) **CLAIM**

An ornamental design for a digital file transfer device, as shown and described.

DESCRIPTION

FIG. 1 is a perspective view of our digital file transfer device.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.

The shading shown in FIGS. 1 through 7 represents color contrast in the claimed design.
